(57) **CLAIM**

The ornamental design for a baby bed, as shown and described.

DESCRIPTION

FIG. 1 is a perspective view of the baby bed showing my new design;

FIG. 2 is a front side view thereof;

FIG. 3 is a rear side view thereof;

FIG. 4 is a left side view thereof;

FIG. 5 is a right side view thereof;

FIG. 6 is a top view thereof; and,

FIG. 7 is an exploded perspective view thereof.

The dashed lines illustrate portions of the baby bed that form no part of the claimed design.
